(57) **CLAIM**

The ornamental design for a jersey-styled apron, as shown and described.

DESCRIPTION

FIG. 1 is an enlarged front perspective view of a jersey-styled apron, showing my new design;

FIG. 2 is a front view of the jersey-styled apron of FIG. 1.

FIG. 3 is a back view of the jersey-styled apron of FIG. 1.

FIG. 4 is a right side view of the jersey-styled apron of FIG. 1.

FIG. 5 is a left side view of the jersey-styled apron of FIG. 1. FIG. 6 is a top view of the jersey-styled apron of FIG. 1; and, FIG. 7 is a bottom view of the jersey-styled apron of FIG. 1. The broken lines in the drawings illustrate subject matter which forms no part of the claimed design.
